UNITED STATES PATENT OFFICE.

JAMES TICHACEK, OF GLEASON, WISCONSIN.

PACKAGE-REACHER.

1,277,778.

Specification of Letters Patent. Patented Sept. 3, 1918.

Application filed September 26, 1917. Serial No. 193,295.

To all whom it may concern:

Be it known that I, JAMES TICHACEK, a citizen of the United States, residing at Gleason, in the county of Lincoln and State 5 of Wisconsin, have invented certain useful Improvements in Package-Reachers, of which the following is a specification, reference being had therein to the accompanying drawing.

10 The present invention has reference generally to improvements in that class of inventions known as store service and more particularly relates to a package reacher.

As the primary aim and object this invention 15 contemplates the provision of a device of the above character designed to be conveniently manipulated and actuated when in the hand of the user so as to be engaged about a package or article normally out of 20 reach of the user thus enabling the user to readily obtain such package or article without occasioning any trouble or inconvenience.

It is an additional object of this invention 25 to provide a package reacher designed to be actuated so that the clamping jaws thereof will be spread preparatory to being placed about a package and subsequent to the release thereof will effectively and tightly 30 clamp the package to consequently assure of the easy removing of the package from its resting place.

More particularly, this invention embraces the provision of a device of the above 35 character wherein relatively movable grippers are operatively connected to the clamping jaws to assure of a quick spreading thereof against the tension of the resilient means which is designed to normally hold 40 the jaws in close relation with respect to each other.

Among the other aims and objects of this invention may be recited the provision of a device of the character mentioned wherein 45 the parts are few, the construction simple, the cost of production low and the efficiency high.

Other improvements and novel details in the construction and arrangement of the 50 various parts of the apparatus will be brought out more in detail in the description to follow, which for a clear understanding of the invention should be considered in connection with the accompanying drawings 55 forming a part hereof; and wherein is disclosed for the purpose of illustration a con-

venient and satisfactory embodiment of the invention. It is to be noted in this connection that minor changes in the construction and arrangement of parts may be made 60 without departing from the principle of operation of the various parts.

The invention is clearly illustrated in the accompanying drawings, in which:—

Figure 1 is an elevation of the device 65 showing the jaws in a closed position;

Fig. 2 is an elevation showing the jaws in an open position;

Fig. 3 is a detail view of the grips;

Fig. 4 is a perspective detail of one of 70 the jaws.

Similar characters of reference are employed in all of the above described views to indicate corresponding parts.

Referring now, more particularly, to the 75 accompanying drawings there is provided a main supporting handle 1 the outer end of which terminates in diverging arms 2 forming a substantial fork. Arcuate package clamping jaws 3 are now provided and are 80 formed at their inner ends with spaced ears 4 for arrangement about ears 5 formed on the terminals of the arms 2. Suitable pivot pins 6 are passed through the adjacent ears for pivotally connecting the jaws to the 85 arms as indicated. The outer ends of the jaws are bent at right angles to the main portions and constitute gripping fingers 7.

In order to normally hold the jaws in close relation with each other suitable 90 resilient means is provided in the present instance, consisting of a coil spring 8, the respective ends of which are fastened to the jaws being preferably engaged in eyes 9 formed on the inner surfaces of the jaws 95 slightly beyond the pivots 5.

As intimated, improved means have been provided for actuating or spreading the jaws against the tension of the resilient means. In reducing this feature of the invention to practice suitable gripping means is employed and consists of a substantially rectangular frame indicated in its entirety by the numeral 10. A ferrule or socket 11 is formed on the inner end of the frame for receiving the inner end of the handle 1. The outer end constitutes a stationary grip 12 while the sides serve as guides 13 about which are slidably engaged the looped ends 14 of the grip 15 movable relative to 110 the stationary grip 12. In operably connecting the movable grip to the jaws suit-

able flexible means are employed and preferably consists of pieces of cord 16. The outer ends of the cords 16 are rigidly connected in loops 17 carried by the rear faces 5 of the jaws at points slightly beyond the eyes 9 while the intermediate portions of the cords are respectively slidably arranged through loops 18 carried by the handle at the point of juncture of the arms and 10 through openings 19 in the inner end of the frame 10 so as to be guided thereby. The inner ends of the cords are fastened to the movable grip preferably in the eyes 20 formed adjacent the ends thereof.

15 In use, the length of the cord 16 is such that when the jaws are in a closed position as shown in Fig. 1 the movable grip will be positioned adjacent the inner end of the frame 10. Upon relative movement of the 20 grips 11 and 12 a pull will be imparted to each cord which acts against the tension of the spring 8 thus causing a spreading of the jaws and enables the user to arrange them about a package by manipulating the 25 handle and subsequent to the release of the grips the spring will act to clamp the jaws on the package whereupon the user may readily obtain such package.

As many changes could be made in the 30 above construction and many apparently widely different embodiments of this invention could be made without departing from the scope thereof, it is intended that all matter contained in the above description 35 or shown in the accompanying drawings shall be interpreted as illustrative and not

in a limited sense. It is also to be understood that the language used in the following claim is intended to cover all the generic and specific features of the invention herein 40 described and all statements of the scope of the invention, which as a matter of language, might be said to fall therebetween.

Having thus fully described this invention, what is claimed as new and desired to 45 be secured by Letters-Patent, is:—

A package reacher including a handle, diverging arms formed on the outer end thereof, arcuate package clamping jaws pivotally mounted on the outer ends of the 50 arms, gripping fingers formed on the ends of the jaws, a coil spring having its respective ends connected to the jaws for normally holding the jaws in close relation with respect to each other, a frame the inner end 55 of which is connected to the opposite end of the handle and provided with openings, the outer end of the frame constituting a stationary grip, a movable grip, loop on the ends of the movable grip and slidably 60 mounted on the sides of the frame, guide eyes mounted on the handle, and flexible cables having their outer ends connected to the eyes on the jaws and their main portions trained through the eyes on the handle 65 and the openings in the frame and also having their opposite ends connected to the eyes on the movable grip so that upon relative movement of the grips the jaws will be spread.

In testimony whereof I affix my signature.
JAMES TICHACEK.
